US0D1083531S

(12) United States Design Patent (10) Patent No.: US D1,083,531 S
(45) Date of Patent:  Jul. 15, 2025

(54) MULTIFUNCTIONAL VEGETABLE CHOPPER AND SLICER

(71) Applicant: Zhejiang Fullstar Houseware Co., Ltd., Taizhou (CN)

(72) Inventor: Congqiang Lu, Taizhou (CN)

() Term: 15 Years

(21) Appl. No.: 35/516,777

(22) Filed: Feb. 24, 2023

(80) Hague Agreement Data

Int. Filing Date: Feb. 24, 2023

Int. Reg. No.: DM/227649

Int. Reg. Date: Feb. 24, 2023

Int. Reg. Pub. Date: Mar. 31, 2023

CLAIM

The ornamental design for a multifunctional vegetable chopper and slicer as shown and described.

DESCRIPTION

1. Multifunctional vegetable chopper and slicer

1.1: Perspective

1.2: Perspective

1.3: Front

1.4: Back

1.5: Left

1.6: Right

1.7: Top

1.8: Bottom

1.9: Exploded

The dash-dash broken lines in the drawings illustrate the portions of the multifunctional vegetable chopper and slicer that form no part of the claimed design.
